UNITED STATES PATENT OFFICE.

NEAL T. MCKEE, OF BRONXVILLE, NEW YORK, ASSIGNOR TO THE SUPERHEATER COMPANY, OF NEW YORK, N. Y., A CORPORATION OF DELAWARE.

STEAM INJECTOR.

Application filed June 19, 1925. Serial No. 38,196.

This invention relates to steam injectors and particularly to that type thereof that is operated by the exhaust steam from an engine. The principal object of my invention is to improve upon a control system for an exhaust steam injector, such as disclosed in United States Patent No. 1,531,004, granted to Malcolm Hard and William A. Buckbee, March 24, 1925.

More specifically the present invention is directed to a construction for regulating the operation of an automatic valve such as disclosed in said co-pending application and which valve is intended to permit the admission of steam to the injector only when live steam is being delivered to the engine.

Exhaust steam injectors of the type to which the present invention relates, are provided with means for supplying live steam to the injector for operating the injector as a live steam injector at such times when the amount of exhaust steam available is insufficient to insure the proper functioning of the injector. In the control system disclosed in the patent above referred to, the automatic valve is caused to operate to cut off the supply of auxiliary live steam to the injector and change over to exhaust steam whenever the throttle of the engine is opened to admit live steam to the cylinders thereof. It has been found, however, to be desirable to prevent the above described operation of the automatic valve from occurring until the engine has attained or exceeded a certain predetermined speed, because at very low speeds the exhaust steam is delivered to the injector in a series of pulsations; the time interval between the pulsations being so great that the continuity of the jet of the injector is interrupted, with the result that the injector spills water between such pulsations.

The principal object of this invention is to prevent the change over of the automatic valve until the engine has reached a certain predetermined speed, thereby overcoming the difficulties above noted. This and other objects will be apparent from the following more detailed description and by reference to the accompanying drawings showing two examples of constructions embodying the principles of my invention. In the drawings Fig. 1 is a side elevation showing some

what diagrammatically a control system according to the present invention installed upon a locomotive; Fig. 2 is a detail of the valve and valve operating means shown in Fig. 1, Fig. 3 is a similar view of a different constructional example, and Fig. 4 is a detailed longitudinal section through the injector.

As shown in Fig. 1, the exhaust steam injector which is indicated generally by the numeral 10, is supplied with exhaust steam through the conduit 11, which is connected with the exhaust steam line of the engine. For the purpose of supplementing the pressure of the exhaust steam, and for operating the injector as a live steam injector, at such times when the supply of exhaust steam is insufficient to secure the desired injector action, live steam is admitted to the injector through the pipes 12 and 13 respectively. This live steam is supplied to the pipes 12 and 13 through the automatic valve 14, connected by the pipe 15 with a steam turret 16. The pipe 13 supplies supplementary live steam which is used to supplement the action of the exhaust steam delivered through the pipe 11, while the pipe 12 supplies auxiliary live steam which is used in connection with the supplementary live steam, and is supplied only at such times when there is no exhaust steam available; the injector working entirely with live steam when the automatic valve is open to supply steam through both of the pipes 12 and 13. The constructional details of the automatic valve 14 form no part of the present invention, but as diagrammatically illustrated is of the type disclosed in the Letters Patent of the United States No. 1,578,978 granted March 30, 1926 to Louis Friedmann and Hans Deutsch.

In order that the operation of the present invention may be clearly understood, a brief description of the operation of the automatic valve is given. With this type of valve is provided a manually operated control valve 17, which, when opened, permits the admission of live steam from the turret 16 to the casing of the automatic valve. This live steam flows through both of the pipes 12 and 13, or through the pipe 13 only, depending upon whether or not exhaust steam is available for operating the injector.

The automatic valve casing is connected by a small pipe 18 with the main steam line of the engine and the automatic valve mounted within said casing is constructed and arranged to prevent the flow of live steam from the pipe 15 to the pipe 12 whenever steam is supplied to the main steam line and there is pressure in pipe 18. If there is no steam supplied to the engine and consequently no pressure within the pipe 18, the automatic valve is moved by the pressure of the steam flowing to the automatic valve casing from the pipe 15 to open the pipe 12 and permit this latter steam to flow through the pipe 12 to the injector. The casing of the automatic valve is also connected by a pipe 19 with a fluid pressure actuated means mounted within the injector 10; said fluid pressure means being adapted to open the exhaust steam valve 21 against the pressure of the exhaust steam flowing through the conduit 11. When the automatic valve is held in position to close the auxiliary live steam pipe, it also opens the pipe 19 to the pressure of the live steam in the automatic valve casing, thus permitting the flow of steam through pipe 19 to operate the fluid pressure means 20 and open the exhaust steam valve 21.

In order to prevent the actuation of the automatic valve to open the pipe 12 and the exhaust steam valve 21 before the engine is operating at a predetermined rate of speed, I propose interposing between the automatic valve and the main live steam line of the engine, a control device, which will prevent the passage of the steam through the pipe 18 until the locomotive has reached a predetermined speed.

In the form shown in Fig. 1 this device consists of a valve 22 having connected to its stem 23 a centrifugal governor 24 arranged to be driven by any suitable means, such as the bevel gears 25, counter-shaft 26, chain 27, and sprockets 28, 29, to cause the governor to open the valve 22 whenever the speed of the locomotive reaches or exceeds a certain definite rate, as for example, five miles an hour.

Any suitable type of governor and valve construction may be employed. In the example illustrated, the valve stem 23 is slidably mounted within a shaft 30, which shaft carries at its lower end one of the bevel gears 25. The governor 24 comprises a pair of balls 31, in accordance with the usual construction of devices of this character, which are connected as by the links 32 with a sleeve 33; said sleeve being rotatable with respect to the valve stem 23, but fixed against longitudinal movement thereon. Rotation is imparted to the governor balls by means of a second sleeve 34 fixedly secured upon the hollow shaft 30 and connected as by the links 35 with the links 32.

The operation of the device shown in Fig. 1 is as follows: Assuming that the handle 17 has been manipulated to supply steam from the turret 16 to the automatic valve, if no steam is being supplied to the engine, that is to say, the throttle of the engine is closed, live steam from the pipe 15 will pass through the automatic valve, to the pipes 12 and 13 by which it will be delivered to the injector. Under these conditions, the injector will operate entirely upon live steam. If now the throttle of the engine be opened, live steam under pressure will flow to the small pipe 18, but will not be permitted to reach the automatic valve casing because of the valve 23 until the locomotive has reached the desired speed. The governor 24 is so adjusted that when the locomotive has reached a speed such that the time interval between pulsations of the exhaust steam available through the pipe 11 is reduced and the flow of steam through the pipe 11 is substantially regular, the valve 22 will open to permit the steam to flow through the pipe 18 to the automatic valve casing. The pressure of this steam will cause the automatic valve to be actuated to the position in which the auxiliary live steam pipe 12 is closed to prevent steam from the conduit 15 from passing through said pipe to the injector, but will permit a limited amount of live steam to pass through the pipe 13 for supplementing the injector action of the exhaust steam through the pipe 11. In this position of the automatic valve, steam is admitted through the pipe 19 to the fluid pressure means 20 and the exhaust steam valve 21 is opened thereby.

In the form shown in Fig. 3 the pipe 18 is placed in communication with the main live steam pipe by means of a valve operatively connected with the reverse lever 40. In this form of the invention, advantage is taken of the practical fact that when the locomotive is running at low speeds, the valve motion is almost invariably placed in full gear, that is to say, the engine is working with full cut-off. When the speed is increased, the cut-off is shortened by moving the reverse lever from the dotted line position shown in Fig. 3 to the full line position. With the form shown in Fig. 3 instead of the governor controlled valve shown in Fig. 1, I employ a slide valve 50 mounted within a steam chest 51. The slide valve 50 has its valve rod 52 connected by means of a link 53 with a sleeve 54, secured to the reach rod 55. Steam is supplied to the valve chest through the pipe 18^a connected with the main steam line of the engine and when the valve is in the position shown in full lines, such steam will pass through the pipe 18 which connects the steam chest with the automatic valve. If the reverse lever 40 is moved to its full gear position for either

reverse or forward travel of the locomotive, the slide valve 50 will be moved so that the communication between pipes 18 and 18^b is cut off and no steam will flow through to the 5 automatic valve.

A suitable stuffing box 57 is provided for preventing leakage of the steam about the valve rod 52.

It will be seen that in both of the constructions herein illustrated I have provided mechanism for automatically preventing the admission of exhaust steam to the injector until the locomotive attains a predetermined rate of speed and also for automatically causing the injector to be operated as a live steam injector when the control valve 17 is opened and when the speed of the engine is below the predetermined rate. It will be understood that the specific constructions herein disclosed are merely illustrative and that many changes, variations and modifications may be resorted to without departing from the spirit of my invention.

25 I claim:

1. In a control system for an exhaust steam injector, conduits connected to said injector for supplying thereto exhaust steam from an engine and auxiliary live steam, an 30 automatic valve for controlling the admission of exhaust steam and live steam to said injector through said conduits, a pipe connecting said automatic valve with the main steam line of the engine, a valve in said pipe 35 and mechanism, connected with a movable element of the engine, for automatically actuating said valve to control the passage of steam through said pipe in accordance with the rate of speed of said engine.

40 2. In a control system for an exhaust steam injector, conduits connected with said injector for supplying thereto exhaust steam from an engine and auxiliary live steam, an automatic valve for controlling the admission 45 of steam to said injector through said conduits, means for admitting fluid under pressure to said automatic valve and mechanism, connected with a movable element of the engine, for preventing the passage of 50 said fluid to said automatic valve when said engine is running below a predetermined rate of speed.

55 3. In a control system for an exhaust steam injector, conduits connected with said injector for supplying thereto exhaust steam from an engine and auxiliary live steam, and mechanism, including an automatic valve and connections to a movable element of the engine, for preventing the admission of exhaust steam to said injector when said engine is operating below a predetermined rate of 60 speed.

65 4. In a control system for an exhaust steam injector, conduits for supplying to said injector exhaust steam from an engine

and auxiliary live steam, and means including an automatic valve and mechanism connected with a movable element of the engine for automatically controlling the admission of steam through said live steam conduit 70 and said exhaust steam conduit respectively, in alternation when the engine is running below and above a predetermined rate of speed.

5. In a control system for an exhaust steam 75 injector, conduits for supplying to said injector exhaust steam from an engine and auxiliary live steam, and means, including an automatic valve, for alternately controlling the admission of steam through said exhaust and 80 live steam conduits, a pipe connecting said valve with the main steam line of the engine, a valve in said pipe, a speed responsive device operatively connected with a moving element of the engine and connections from 85 said speed responsive device to said last named valve.

6. In a control system for an exhaust steam injector, conduits for supplying to said injector exhaust steam from an engine 90 and auxiliary live steam, and means, including an automatic valve, for alternately controlling the admission of steam through said exhaust and live steam conduits, a pipe connecting said valve with the main steam 95 line of the engine, a valve in said pipe, and connections from said valve to a movable element connected with the engine and whose position is indicative of the speed of the engine for preventing the passage of steam 100 through said pipe to said automatic valve when said engine is running below a predetermined rate of speed.

7. In a control system for an exhaust steam injector, conduits for supplying to 105 said injector exhaust steam from an engine and auxiliary live steam, and means including an automatic valve and a speed responsive device connected with a movable element of the engine, for automatically controlling 110 the admission of steam through said live steam conduit and said exhaust steam conduit respectively in alternation when the engine is running below and above a predetermined rate of speed.

115 8. In a control system for an exhaust steam injector, a conduit for supplying to said injector exhaust steam from an engine, an exhaust steam valve adapted to be closed normally by the pressure of the exhaust 120 steam in the exhaust steam conduit, fluid pressure operated means for opening said valve against the pressure of the exhaust steam, an automatic valve having a pair of pipes connected therewith, one of said pipes leading to said fluid pressure means and the other to the main steam line of the engine, an auxiliary live steam conduit connecting said injector and automatic valve, said automatic valve being constructed and arranged to 125 130

4
permit the passage of steam to said auxiliary live conduit when no steam under pressure passes through said other pipe, and to open said first pipe when steam under pressure passes through said other pipe; and mechanism connected with a movable ele- ment of the engine for preventing the passage of steam through said other pipe when said engine is operating below a predetermined rate of speed. In testimony whereof I have hereunto set my hand.

NEAL T. McKEE.
